UNITED STATES PATENT OFFICE.

ROBERT HOPE-JONES, DECEASED, LATE OF NORTH TONAWANDA, NEW YORK, BY CECIL HOPE-JONES, TEMPORARY ADMINISTRATRIX, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

MECHANISM FOR PRODUCING SFORZANDO EFFECTS IN ORGAN-PLAYING.

1,325,294.

Specification of Letters Patent. Patented Dec. 16, 1919.

Application filed November 14, 1914. Serial No. 872,177.

To all whom it may concern:

Be it known that ROBERT HOPE-JONES, deceased, late of North Tonawanda, in the county of Niagara and State of New York, invented certain new and useful Improvements in Mechanism for Producing Sforzando Effects in Organ-Playing; and the following is hereby declared to be a full, clear, and exact description of the same, reference being had to the accompanying drawings forming a part of this specification, and to the reference-numerals marked thereon.

The present invention relates to organs or other musical instruments, and it has for its object to provide means for emphasizing a given note, chord or series of notes or chords to produce the effect which is termed in musical parlance, a sforzando, meaning a sudden and powerful attack immediately followed by a diminuendo or reduction in power of tone, whereby a single tone or chord is rendered prominent. The invention has for its further object to provide, in conjunction with the shutters or shades of an organ swell box and the key board of the organ, a system of electric circuits and magnets controlled thereby, which may be energized by the depression of a key to control said shutters together with a circuit-switching mechanism independently controlled by the operator, whereby one or more of the shutters may be opened upon the depression of a key according to the volume of the tone which it may be desired to produce. To these and other ends the invention consists in certain improvements and combinations of parts, all as will be hereinafter more fully described, the novel features being pointed out in the claims at the end of the specification.

In the drawings:

Figure 1 is a diagrammatic view illustrating an arrangement of parts in accordance with the present invention the organ keys being shown as inverted;

Fig. 2 is a detail view illustrating the mechanism employed for rocking the swell shade or shutter, and showing the position of the parts when the corresponding shutter is closed;

Fig. 3 is a detail view illustrating the multiple switch, and

Fig. 4 is a detail fragmentary view showing one of the organ keys and its contacts in side elevation, the key being shown in normal position.

Similar reference numerals throughout the several views indicate the same parts.

Prefacing the description of the invention, it may be briefly stated that in the construction of organs, especially those of the larger size equipped with a greater number of stops, he has introduced the custom of mounting the different departments such as the wood, wind, brasses, and stringed instruments in different compartments or rooms closed by the folding doors or shutters which are generally known as swell shades. These might be connected for simultaneous operation and attached to a common motor device, but this arrangement of the parts, while permitting the control of the volume of sound, possesses the disadvantage that the effect of producing a given note with attack, or forcing it, to bring out the emphasis in a passage of music is impossible.

For this reason he has mounted the swell shades or shutters for independent action and connected each of them to a separate motor mechanism and then arranged said mechanism so that one may be operated alone, or a series of them actuated in unison.

In illustrating the invention he has shown, in Fig. 1, a sound room or compartment 1, closed at one side by a series of shutters or swell shades, *a*, *b*, *c*, *d*, *e*, and *f*, each of which is pivoted at its ends on suitable journals or bearings which are indicated at *a'*, *b'*, etc., on which they may be rocked from the closed position shown in full lines in Fig. 1 to the open position shown in dotted lines. The motor devices for opening the shutters or shades are indicated by *a²*, *b²*, etc., and comprise bellows or pneumatics, which are connected with the shutters by suitable rods *a³*, *b³*, etc. The several pneumatics *a²*, *b²* are preferably mounted on a common wind chest 2, containing air under pressure. Separate passages, such as indicated by *a⁴* in Fig. 2,

are provided to afford communication from the wind chest to the bellows but the flow of air therethrough is normally cut off by the valve head 3, constituting a secondary 5 valve which is mounted on the stem 4 and reciprocated by the bellows 5, said stem also carrying the valve head 6 adapted to close the outer end of the passage a^4 and to shut off communication with the atmosphere 10 when said passage is opened by the valve head 3 and connected to the wind chest 2. The primary valve which controls the action of the bellows 5 consists of a casing 7 having the interior passage 15 8 communicating with said bellows and provided with the ports 8^a and 8^b , the former being normally open and leading into the wind chest 2, while the latter which open into the atmosphere are normally 20 closed by the valve head 9 adapted to be attracted by the electromagnet 10 to reverse the normal condition of said ports. Thus, when the magnet is energized, the port 8^a is closed, the bellows 5 collapses, 25 and the position of the secondary valve heads 3 and 6 reversed, which causes the simultaneous expansion of the bellows a^2 to cause the opening of its respective swell shade a . When the valve head 9 is raised, 30 the valve heads 3 and 6 are returned to the position shown in the drawings and the bellows a^2 is collapsed, closing the swell-shade in a well-known manner. This closing action of the shades may be effected by springs 35 of any suitable construction which may be applied directly to the shades or to their actuating bellows. In the construction shown in the drawings, by way of example, each shade is provided with such a spring 40 a^5 secured at one end to the shade below its pivot and at its other end to the wind chest 2, or other fixed part. It will be understood that the mechanism just described, or an equivalent arrangement of 45 parts, is provided for actuating each of the swell shades and that the magnet controlling each primary valve is arranged in a branch circuit comprising a wire 11 common to the several magnets and connected 50 with one side of a source of electrical energy, such as a battery α . The other side of the circuit of each primary valve magnet comprises an individual wire, such as a^{10} , b^{10} , c^{10} , d^{10} , e^{10} f^{10} , through which the circuits 55 of said magnets may be completed when these conductors are connected to the other side of the battery through the agency of a suitable switching mechanism.

The switching mechanism interposed between 60 the battery and one side of the circuit of each of the primary magnets is adapted for both manual and automatic operation, the latter being accomplished through the action of the organ keys when 65 a given stop key, which in this instance

would be labeled "Sforzando", is set or thrown into its operative position.

This switching mechanism may be constructed in a simple manner by providing, at the ends of the circuit wires a^{10} , b^{10} , etc., 70 switch arms or wipers a^{11} , b^{11} , etc., which normally engage corresponding contacts connected to wipers a^{12} , b^{12} , the free ends of which rest upon the periphery of a drum or commutator 12. The latter is provided 75 with a metallic section 13, having an edge 14 disposed diagonally and so positioned that upon rotation of the drum in one direction it will successively engage the wipers a^{12} , b^{12} , etc. The portion 13 of the drum is 80 connected with the other side of the battery α by a suitable means, such as a wiper 13^a and wire 13^b.

In order to produce a satisfactory "sforzando" effect it is unnecessary to provide for the momentary opening of more than two of the swell shades and as this is an effect which it is desirable to produce automatically, he provided, in addition to the wipers before described, two other brushes 90 a^{13} , b^{13} , which are normally in contact with the conducting portion 13 of the commutator, as shown in Fig. 1 and into engagement with which the two switch arms a^{11} , b^{11} , are moved when the "sforzando" stop 95 key "Sf" is thrown into operative position, as shown in the same figure.

The switch arms a^{11} , b^{11} are shifted from the normal position to that indicated by dotted lines by means of a rod 15 connected 100 to a bellows g , associated with the wind trunk 20, and expanded in precisely the same manner as the bellows a^2 and contracted by a suitable spring 15^a. Its action is controlled by a primary valve governed by the magnet 105 g' arranged in a circuit comprising wires g^2 and g^3 , the former leading to one side of a source of current, such as a generator g^{12} , while the latter, after passing through a series of key contacts and a master switch 110 continues to the other side of the generator. The wire g^3 is connected to the last contact g^7 of a series of contacts g^5 , ending in the one indicated by g^6 from which leads the wire g^7 in which is disposed a pair of contacts g^8 , g^9 , the last mentioned contact being connected by the wire g^{10} to the source of current g^{12} . The "sforzando" stop-key Sf is provided with a contact g^{11} , which when the key is thrown into operative position 115 120 bridges the pair of contacts g^8 , g^9 , as shown in Fig. 1.

The series of contacts g^5 are arranged in pairs beneath the organ keys indicated by h , i , j , and k , these being some of the note-controlling keys of the ordinary manual. The circuit through these pairs of contacts is completed when the keys are in their normal position by the contact or switch plates h' , i' , j' , k' . Fig. 4 shows the normal posi- 125 130

tion of these keys. They control the sound-producing parts, like ordinary organ keys, causing a pipe to speak whenever the corresponding key is depressed. From this arrangement of the parts it will be seen that when the key stop S_f is depressed the organ keys being in normal position the primary magnet g' will be energized and the bellows g distended to shift the several switch arms a^{11}, b^{11} , etc., to the dotted line position. The circuits of two of the primary magnets 10, controlling the bellows a^2, b^2 , will be completed through the wipers a^{13}, b^{13} , with the result that said bellows will be inflated and the swell shades or shutters a and b will be held in the open position until one of the keys h, i, j, k , is depressed. Movement of one of these keys to the intermediate position shown by dotted lines in Fig. 4 will destroy the circuit of the primary magnet g' and permit the bellows g to collapse and restore the switch arms a^{11}, b^{11} , etc., to their normal position where they will remain so long as the performer retains one or another of the keys depressed. When, however, in rendering a given selection of music, the keys are all released at the same time and the circuit of magnet g' completed, the switch arms are oscillated again into the dotted line position and the shutters a and b again opened so that the attack or emphasis is given automatically to the next note which is sounded by the depression of a key. All keys representing tones which it may be desired to emphasize, as above described, are provided with such switch or make-and-break contacts h^1, i^1 , etc.

The drum or commutator 12 will, in practice, be preferably located beneath the console sole in position to be controlled by a pedal P , Fig. 3, shown connected by a link p' with a crank arm p^2 attached to one end of the drum. The rotation of this drum by means of the pedal P enables the player to control the volume or surging effect of the sound emitted, by causing the section 13 to complete the circuits of one or more of the primary magnets controlling the shutters a, b, c, d, e and f . It will be understood that by rocking the pedal these circuits may be opened and closed successively, the position of the commutator determining the number of the shutters which are held open at any given time.

The shifting of the contact arms a^{11}, b^{11} , etc., from the position shown in dotted lines to that indicated by full lines occurs upon the breaking of the circuit of the magnet g' by the rocking of one of the keys to the dotted line position, shown in Fig. 4. To enable the volume of tone produced in the attack upon a note, or set of notes, to be sustained, if desired, additional contacts are arranged on the keys at the opposite sides of their pivots so that the circuit of the magnet

g' , when broken at one place, will be immediately completed through another set of contacts. The last mentioned effect is produced by inserting between the wires g^3 and g^7 a bridge, comprising the wires g^{30} and g^{70} , each of which has a plurality of branches terminating in a multiple group of contacts g^{50} , arranged in pairs beneath the respective keys h, i, j and k . Coöoperating with said last mentioned pairs of contacts are contact plates h^{11}, i^{11}, j^{11} and k^{11} , by means of which the player may, by depressing a key sufficiently, close the circuit of the magnet g' through the bridge g^{30}, g^{70} , immediately following the opening of the main circuit g^3, g^7 .

The mechanism illustrated and described comprises a plurality of shutters, some of which are normally open when the sforzando key is closed, to give the effect known as an attack, and which are adapted to be closed upon touching or partly depressing one or more of the organ keys. The arrangement of the parts is such that if the musician makes a long or marked break for his "phrase" he will obtain a marked "sforzando" following the break. On the other hand, if he makes his "phrase" break very short the following sforzando will be small or not so loud, the shortening of the "phrase" break not allowing time for the normally open shutters to return to their full open position after having been closed.

I claim as the invention:

1. The combination with an organ key, an organ swell chamber having an opening, and a shutter normally closing said opening, of means for opening the shutter, and means under the control of said organ-key for controlling the closing movement of the shutter.

2. The combination with an organ swell box containing sound producing devices and having an opening, a shutter controlling the opening and an organ key for effecting the actuation of a sound-producing device, of mechanism for operating the shutter, controlled by the key to close the shutter, and means for operating the shutter independently of the key to open it.

3. The combination with a swell chamber having an opening therein, and a shutter normally closing the opening of a sforzando key, an organ key for controlling a sound-producing device, and means controlled by the sforzando key and the organ key for opening the shutter.

4. The combination with a swell-chamber having an opening therein, and a shutter normally closing the opening of a sforzando key, an organ key for controlling a sound-producing device, mechanism for opening the shutter, and a circuit including said mechanism and controlled by the sforzando key and the organ key.

5. The combination with a swell chamber and a shutter normally closing an opening therein, mechanism for opening the shutter, and a circuit for operating said mechanism, of a sforzando key for closing said circuit, an organ key for controlling a sound-producing device, and a contact in said circuit opened by actuation of the organ key. 50
6. The combination with a swell chamber and a shutter normally closing an opening therein, mechanism for opening the shutter, a circuit controlling said mechanism and a switch in the circuit, of closing mechanism for the switch, a second circuit including the switch-closing mechanism, a sforzando key for closing the last named circuit, an organ key controlling a sound producing device, and a contact in said second circuit opened by actuation of the organ key. 60
- 10 7. The combination with a swell chamber and a plurality of shutters normally closing openings therein, a mechanism for opening each shutter, a separate controlling circuit for each mechanism and a switch whereby a predetermined number of the circuits may be closed, of a switch-closing mechanism, a circuit therefor, a sforzando key in the last-named circuit, an organ key, and a contact in said last-named circuit opened by actuation of the organ key. 70
- 15 8. The combination with a swell chamber, a plurality of shutters normally closing openings therein, mechanism for opening each shutter, a branch circuit for controlling each mechanism, a switch under the operator's control whereby a desired number of said branch circuits may be closed and supplemental switches for closing a predetermined number of the remaining branch circuits, of a closing mechanism for the last-named switches, a circuit for said closing mechanism, a sforzando key in the last-named circuit, an organ key, and a contact in the last-named circuit opened by actuation of said organ key. 80
- 20 9. The combination with a swell-chamber, a plurality of shutters normally closing openings therein, a mechanism for opening each shutter, a main circuit, a plurality of branch circuits, one for each mechanism, switches 50 in the branch circuits connected for simultaneous operation, a series of contacts in excess of the number of said switches with which the latter coöperate, the excess contacts being normally idle and permanently connected to the main circuit, and a switch under the operator's control adapted to be progressively connected to the normally active contact members, of shifting mechanism for moving said switches to engage the normally idle contacts, a second circuit for operating said shifting mechanism, a sforzando key for closing said second circuit, an organ key, and a contact in said second circuit opened by actuation of the organ key. 65
- 25 10. The combination with a swell-chamber, a shutter normally closing an opening therein, mechanism for opening the shutter, a circuit controlling said mechanism, and a switch in the circuit, of closing mechanism for the switch, a second circuit including the switch-closing mechanism, a sforzando key for closing said second circuit, a series of organ keys, and contacts arranged in series in said second circuit, each contact being opened by actuation of one of said organ keys. 75
- 30 11. The combination with a swell-chamber, a shutter normally closing an opening therein, mechanism for opening the shutter, a circuit controlling said mechanism and a switch in the circuit, of closing mechanism for the switch, a second circuit including the switch closing mechanism, a sforzando key for closing the second circuit, a series of organ keys, contacts arranged in series in said second circuit, each contact being opened by depression of an organ key to one position and other contacts arranged in multiple in said circuit, each of which is closed by depression of an organ key to another position. 85
- 35 40 45 50 55 60 65 70 75 80 85 90
9. The combination with a swell-chamber, a plurality of shutters normally closing openings therein, a mechanism for opening each shutter, a main circuit, a plurality of branch
